UNITED STATES PATENT OFFICE

1,950,825

MEANS FOR PREHEATING THE AIR SUPPLY
TO A GAS PRODUCER

Axel Svedlund, Orebro, Sweden

Application March 19, 1930, Serial No. 437,184
In Sweden March 11, 1929

1 Claim. (Cl. 48—64)

The object of this invention is to increase the efficiency and improve the economy of plants for generating power from gas, especially producer gas for internal combustion engines. In 5 such plants a gas-producer, a cooler for the gas leaving the producer, a fan propelling air for cooling the cooling medium of the engine and a gas purifier generally are provided.

The manner in which the said members have 10 been combined and have co-operated, however, leave a great deal more to be desired, for which reason the efficiency and the economy have not been satisfactory.

The present invention is characterized chiefly 15 by the fact, that the said members are so combined, that the cooler of the producer gas and the cooler of the cooling medium of the engine are located by each other in the direction of the air current supplied by the fan, so that the same 20 air current is used for cooling both the said coolers, and that behind the coolers in the direction of the air current the mouth of the pipe supplying air to the gas producer is located, so that partly the air preheated by the coolers passes into the 25 said pipe and is then still more heated while passing to the producer, and partly an excess of pressure is imparted to the said air.

Further characteristic features of the invention 30 will be clear from the following description of the form of execution of the invention illustrated as an example in the accompanying drawing.

Fig. 1 is a side view with some parts in section of the producer, the coolers and pipe connections. Fig. 2 is a front view of the gas cooler.

35 1 is the gas producer, which preferably is made of iron and provided with a fire-proof lining. The top part 2 of the producer constitutes the chamber, into which fuel is introduced. The said chamber is provided with a cover 3. The inner cross section of the producer is contracted at 4, a distance below the cover and is then widened, so that the lower part or the chamber 5, in which the gas is produced, is wider. The said chamber 5 is provided at its bottom with a grate 6. Air 40 effecting the combustion is introduced at the contracted part 4 of the producer and through a pipe 7. In the producer, which works in accordance with the so-called inverted system, the produced gas escapes from the chamber 8 under the 45 grate 6 through a pipe 9, in which it passes to the gas cooler 10.

The gas is introduced at 11 into the chamber 12 of the cooler, passes from the same downwards through a group of narrow channels 13 to a chamber 14 and further through a group of channels

15 in opposite direction to the chamber 16. The channels may be divided into a greater number of groups if necessary. The main thing is that the direction of the gas current is changed in order that a mixing may be effected, because the 60 gas when passing in one direction only is cooled only at the surfaces of the gas columns, while the core is cooled in a degree not worth mentioning. The gas leaves the cooler at 17 and passes through a pipe to a gas purifier, which is not shown in 65 the drawing and may be constructed in any suitable manner, for instance of the type, which is based on the centrifugal action, so that heavy particles are forced outwards and separated from the lighter gas.

The cooler 10, Fig. 1, is cooled by means of air, which is forced through the same by a fan 18 and sweeps round the walls of the channels 13 and 15. Near the said cooler 10 a second cooler 19 is provided for the cooling medium of the engine. 70 The same air current, which has passed through the cooler 10, passes also the cooler 19 and cools the same. The ordinary cooler of the engine may be used.

Owing to the described arrangement the same 80 air current propelled by the fan will cool both the gas leaving the producer and the cooling medium of the engine and only one fan is necessary. Preferably, the cooler 19 of the cooling medium of the engine is located behind the cooler 10 of 85 the gas in the direction of the air current. In certain applications of the invention it may be preferred to place the said apparatus in the reversed order. In certain cases the cooler 10 of the gas may be divided into two different parts, 90 located at different parts of the gas current.

Behind the coolers 10 and 19 in the direction of the air current a funnel-shaped enlargement 20 of the pipe 7, supplying air to the producer, is located. Owing to this arrangement an excess 95 of pressure is imparted to the air. Pipe 7 leads to the producer. In order that the air passing from the coolers and heated by the same may be still more pre-heated the pipe 7 may be mounted inside the pipe 9, as shown in Fig. 1. The air 100 pipe may, however, be located round the gas pipe, if wanted.

Under certain circumstances, for instance when anthracite is used as fuel, it may be advantageous to add to the air necessary for the production of the gas a certain quantity of steam. In the form of execution shown in the drawing the arrangement for the said purpose is as follows:

21 is a reservoir for water located at a level suitable for gaining the proper height of the 110

water. Water passes from the reservoir 21 through a pipe 22 to a pipe 23 located inside the gas pipe 9. The water contained by the said pipe 9 is heated and the produced steam passes at 5 24 into the pipe 7 and accompanies the air and is further heated (pre-heated) partly while passing to the chamber 8 and partly inside the same.

By means of the devices described above a combustible gas having a great heat capacity and a 10 great purity may be produced from charcoal and wood. To this result attributes in a very high degree the effective pre-heating of the air previously to its entrance into the producer, which is of an especially great importance at a variable 15 load of the engine, when the consumption of gas is not uniform and in its turn has the tendency of involving the generating of a gas with low heat capacity at a bad pre-heating of the air.

Owing to the fact that the air is supplied to 20 the gas producer at an additional pressure an increased capacity of producing gas per cm.² of the area of fire room is gained and hereby a sufficient 25 quantity of gas will be rapidly produced at a sudden increasing of the load. Further, the fan operated manually and previously necessary for starting the producer is dispensed with.

The gas purifier mentioned above permits a 25 very high temperature of the gas, which involves the advantage that it may be located also before the cooler of the gas, so that the channels of the 30 gas cooler are not rendered dirty. During certain circumstances it may be necessary to provide an extra purifier of the gas before it enters the engine.

Through the described means for generating 35 and supplying steam the quantity of the same agrees with the quantity of gas, so that the control is automatic.

The greatest advantages of the device described above compared with devices previously used consist in that it operates with a high efficiency i. e. that a great amount of mechanical energy per unit of volume or weight of the device is gained, and with a great mechanical efficiency i. e. that a great amount of mechanical energy per each kilogram of fuel is gained. The said advantages render it possible to run for instance vehicles (traction engines and the like) by means of a cheaper solid fuel, for instance charcoal, while it has been possible previously only to use a liquid fuel. What an enormous importance these facts will have in the near future may be best comprehended from the fact that experimental engines, manufactured especially for traction engines, involve running expenses amounting to only one half of the expenses for running an engine of the same capacity by means of crude naphtha. To this may be added, that the expenses for the plant are slight in comparison with previous constructions.

I claim:

Means for introducing preheated air into gas producers utilized for feeding internal combustion engines, a cooler for the producer gas, coolers for the engine cooling medium, said coolers being arranged one behind the other, said means comprising a fan located behind the coolers, a tube introducing air into the gas producer, a funnel-shaped air inlet on the end of said tube, said funnel-shaped air inlet being located behind the fan, whereby the air current produced by the fan and preheated when passing the coolers is being forced under pressure by the fan through said tube into the producer.

AXEL SVEDLUND.
